BUFFING AND POLISHING DEVICE

Maynard L. Monger, deceased, late of Royal Oak,
Mich., by Beatrice W. Monger, administratrix,
Detroit, Mich., assignor to Beatrice W. Monger

Application May 19, 1950, Serial No. 162,922

7 Claims. (Cl. 51—192)

1

This invention relates generally to buffing or polishing tools, and more particularly to a rotary buffing or polishing wheel of the type in which an abrasive sleeve is supported on an inflated flexible cylinder.

It is an object of this invention to provide a buffing and polishing tool of the aforementioned type, in which an inflatable rubber cylinder is supported on a central hub structure and sealingly connected therewith in a novel, simple and efficient manner.

It is a still further object of this invention to provide in a buffing and polishing tool of the aforementioned type, a novel and inexpensive hub construction and arrangement for connecting the same with the inflated cylindrical bag or member.

It is a still further object of this invention to provide a buffing and polishing tool of the aforementioned type which can support one or more sleeves of abrasive material, which can be easily inflated or deflated to properly support the abrasive sleeve, and which can be easily assembled and disassembled.

It is a still further object of this invention to provide a durable, compact, lightweight and inexpensive buffing and polishing tool, in which the abrasive sleeve is supported by a flexible cylindrical backing member from end to end.

These and other objects of this invention will become apparent from the following detailed description, taken in conjunction with the accompanying drawing, in which:

Figure 1 is an end elevational view of the tool of this invention;

Fig. 2 is an enlarged cross sectional view of the structure illustrated in Figure 1; and

Fig. 3 is a sectional view of the structure illustrated in Fig. 2, taken along the line 3—3 thereof.

Referring now to the drawing, it will be seen that the buffing and polishing tool of this invention includes a hub 5, which is composed of a pair of end to end aligned members 7 and 9, which are annular in cross section. The member 7 is recessed at 11 to telescopically receive the adjacent end of the member 9, and the member 9 is provided with an annular flange 13 which engages the inner periphery of an annular cavity 15 in the member 1, so as to aid in maintaining the hub members 7 and 9 in proper alignment. The members 7 and 9 are formed separably, and preferably from molded plastic, and are detachably interconnected. The member 7 is formed with a passageway 17 which extends from the cavity 15 through one end thereof and in which a headed valve stem 19 is inserted, so that the head 21 is disposed in the cavity 15, prior to the assembly of the two hub members 7 and 9. A rubber seal 23 is disposed between the valve stem head 21 and the adjacent wall of the cavity 15,

2

while a nut 25 is threaded on the exterior end of the valve stem 19, so as to draw the head 21 against the seal 23 and the wall of the cavity to provide an air tight seal between the valve stem and the hub. The valve stem contains a conventional valve 24, such as a Schroeder valve, and is adapted to be connected with a suitable air pump, or compressed air outlet, for reasons which will hereinafter appear.

Disposed adjacent the opposite end faces of each of the hub members 7 and 9 are end plate members 27 and 29 respectively. The plate member 27 is provided with a central opening 31, through which the exterior end of the valve stem 19 projects. The plate member 29 is provided with an inwardly extending threaded opening 37, in which a spindle of a rotary drive mechanism may be inserted and connected for rotatably driving the tool.

20 A flexible, air impervious cylinder or bag 39, made preferably of rubber, surrounds the hub 5 and end members 27 and 29, and includes a peripheral wall 41, the thickness of which is increased in the center at 43 to aid in preventing

any bulging of the cylinder when it is inflated, as will hereinafter appear. The peripheral wall 41 of the cylinder is spaced from the periphery of the hub 5, so as to provide an air space 45 between the hub and cylinder peripheral wall. The cylinder 39 is formed with annular end walls or portions 47, which extend radially inwardly from each end of the peripheral wall 41 and each of which terminates in an annular second wall portion 49, which extends inwardly substantially parallel to the peripheral wall 41. An annular flange 51 extends radially inwardly from the inner end of each second wall portion 49, which is of a dovetail shape in crosssection. The annular wall portions 47 and 49 of the cylinder 39

35 are constructed, as can be seen in Fig. 2, so that there will be no tendency for the cylinder, when it is inflated, to blow out or bulge adjacent the ends thereof, while at the same time, flexibility is still provided from one end to the other of the cylinder.

40 The opposite end faces of the hub members 7 and 9 are notched back or recessed at 53, adjacent their outer periphery, and the inner faces of the end members 27 and 29 are likewise notched back or recessed at 55 so that when the end members are properly assembled and positioned with respect to the hub member, the recesses 53 and 55 will coact to provide an annular recess or groove at each end of the hub, which is of a dovetail shape in cross section and in which the adjacent dovetail flange 51 of the cylinder 39 is received.

45 It should also be noted that the outer periphery of each of the end members 27 and 29 engages the inner periphery of the adjacent second

wall portion 49 of the cylinder 39, so as to aid in supporting the adjacent end of the cylinder. Cap screws 59 extend longitudinally through the end member 27 and hub 5, and have their shank ends threaded into tapped openings 61 in the end member 29, while the head 63 of each cap screw engages the outer face of the end member 27. By threading the studs 59 into the end member 29 the end members 27 and 29 will be drawn toward each other and into the proper aligned relationship with the hub members 7 and 9. When the end members 27 and 29 are drawn toward each other by the tightening of the cap screws, the annular dovetailed flange 51 of the cylinder 39 will be sealingly clamped between the end members and the hub members 7 and 9 to provide a positive and effective seal between the inflatable cylinder 39 and the central hub structure. This dovetailed construction assures maximum sealing and at the same time provides a suitable means for properly supporting the rubber cylinder on the central hub structure, in a relatively simple and inexpensive manner.

When the buffing and polishing tool is in use, a sleeve 65 of abrasive material such as sand-paper, emery cloth or the like, is inserted over the peripheral wall 41 of the cylinder. The cylinder is then inflated by connecting the valve stem 19 with an air pump or compressed air outlet, and the air flows through the valve stem into the hub cavity 15. The air flows from the hub cavity 15 through a passageway 67 in the hub member 7, to the air space 45 between the hub and the cylinder peripheral wall, in order to inflate the cylinder or bag 39. By inflating the cylinder the peripheral wall will frictionally engage the abrasive sleeve 65, and if desired several abrasive sleeves or a continuous wrapping of abrasive material may be applied to the outer periphery of the cylinder for buffing and polishing operations or the like. The cylinder may be easily deflated by letting air out through the valve stem 19 to enable the abrasive sleeve to be easily removed, and the entire device may be easily assembled and disassembled, due to the construction previously illustrated and described.

It will thus be seen that a simple, efficient and durable buffing tool of the type in which an inflatable rubber cylinder provides a flexible backing member for an abrasive sleeve, is provided, which is of a relatively light weight and which may be easily connected with any suitable driving mechanism, or the like, for rotation of the same. Also because the abrasive sleeve is flexibly backed throughout its length the tool has a large variety of uses in the polishing and buffing field.

What is claimed is:

1. A buffing and polishing wheel including a hub composed of a pair of separable members disposed in an end to end aligned relationship, one of said members having a cavity therein adjacent the other of said members and a passageway communicating with said cavity and extending through one end thereof, a headed valve stem extending through said passageway and having the headed end thereof disposed within said cavity, platelike clamping elements disposed adjacent the opposite ends of said hub members, one of said elements having an opening therein through which said valve stem extends, the opposite ends of said hub members and each of said platelike elements being recessed so as to coact to provide annular recesses which are of a dovetail shape in cross section, a cylindrical flexible

element surrounding said hub and plate-like elements, the peripheral wall of which is spaced from said hub so as to provide an air space therebetween, end portions extending radially inwardly from the opposite ends of said peripheral wall and including an annular portion which is of a dovetail shape in cross section and disposed within said annular dovetail recess formed in said hub and platelike elements, means interconnecting said platelike elements and clamping said dovetail portions between said elements and said hub so as to provide a sealed connection, and passageway means in said hub communicating said hub cavity with the air space between said cylindrical member peripheral wall and said hub.

2. A polishing and buffing tool including a hub, a hollow flexible cylinder surrounding said hub and providing an air space between said hub and the peripheral wall of said cylinder, an annular end wall extending radially inwardly from each end of said cylinder peripheral wall and terminating in a second annular wall extending longitudinally inwardly substantially parallel to said peripheral wall, an annular flange extending radially inwardly from said second wall and being of a dovetail shape in cross section, the opposite ends of said hub being recessed so as to receive a portion of each of said dovetail flanges, annular end members disposed adjacent said hub ends and having the outer periphery thereof engaging the inner periphery of each of said second annular walls, said end members being recessed to receive a portion of each of said dovetail flanges so that said flanges are confined between said hub and end members, means interconnecting said end members and sealingly retaining said flanges between said end members and said hub, exteriorly accessible valve means supported in said hub and communicating with the air space between said hub and cylinder member peripheral wall to permit said cylinder to be inflated.

3. A buffing and polishing tool including a hub composed of a pair of separable end to end members having the adjacent ends in telescopic engagement, one of said members having a cavity therein adjacent the other of said members and a passageway communicating with said cavity and extending through one end of the member, a valve stem extending through said passageway and having the headed end thereof disposed within said cavity, platelike clamping elements disposed adjacent the opposite end faces of said hub members, one of said elements having an opening therein through which said valve stem extends, a cylindrical flexible element surrounding said hub and platelike elements, the peripheral wall of which is spaced from said hub so as to provide an air space between the hub and element peripheral wall, said cylindrical flexible element including end wall portions extending radially inwardly from the opposite ends thereof, the opposite ends of said hub members and each of said platelike elements being recessed so as to coact to provide annular recesses in which are received the inner ends of the cylindrical element wall portions, means interconnecting said platelike elements and clamping said wall portions between said clamping elements and said hub so as to sealingly connect said cylindrical element with said hub, and passageway means in said hub communicating said hub cavity with the air space between said cylindrical member peripheral wall and said hub.

4. A buffing and polishing tool including a hub

composed of a pair of separable members disposed in an end to end aligned relationship, one of said members having a cavity therein and a passageway communicating with said cavity and extending through one end thereof, a headed valve stem extending through said passageway and having the headed end thereof disposed within said cavity, annular platelike clamping elements disposed adjacent the opposite end faces of said hub member, one of said elements having an opening therein through which said valve stem extends and the other of said elements being adapted to be connected to a rotating spindle, the opposite end faces of said hub members and the adjacent faces of said platelike elements being annularly recessed so as to coact to provide annular recesses at each end of the hub which are of a dovetailed shape in cross section, a hollow flexible cylinder surrounding said hub and providing an air space between said hub and the peripheral wall of said cylinder, an annular end wall extending radially inwardly from each end of said cylinder peripheral wall and terminating in a second annular wall extending inwardly substantially parallel to said peripheral wall, an annular flange extending radially inwardly from said second wall and being of a dovetail shape in cross section, each of said annular flanges being disposed in one of said annular recesses so as to be confined between said hub and platelike elements, the outer periphery of each of said platelike elements engaging the adjacent inner periphery of said cylinder second annular wall, means interconnecting said platelike elements and said hub members so as to sealingly retain said cylinder flanges between said platelike elements and said hub, and passageway means in said hub communicating said hub cavity with the air space between said cylinder and said hub.

5. A polishing and buffing tool including a hub, a hollow, flexible, air impervious cylinder surrounding said hub and providing an air space between said hub and the peripheral wall of said cylinder, an annular end wall extending radially inwardly from each end of said cylinder peripheral wall and terminating in a second annular wall extending longitudinally inwardly substantially parallel to said peripheral wall, an annular flange extending radially inwardly from said second wall, the opposite ends of said hub being recessed so as to receive a portion of each of said flanges, annular end members disposed adjacent said hub ends and having the outer peripheries thereof engaging the inner peripheries of said second annular walls, each of said end members being recessed to receive a portion of one of said flanges so that said flanges are confined between said hub and end members, means interconnecting said end members and sealingly retaining said flanges between said end members and said hub, and exteriorly accessible valve means supported by said hub and communicating with the air space between said hub and cylinder member peripheral wall for enabling the flexible cylinder to be inflated.

6. A hub on which an inflatable flexible cylinder is mountable comprising a pair of separable interfitting hub portions, one hub portion having an axial circular cavity, the other hub portion having an axial annular projection, an air passageway and control valve in the said hub portion for regulating the flow of air between its axis and periphery, an annular platelike mem-

ber adjacent to the said hub portion and around the said control valve having an inner peripheral recessed edge forming a dove-tailed recess in conjunction with an outer peripheral recessed edge on the said hub portion, the other said hub portion having a partial axial recess, a second platelike member adjacent to the said other hub portion and extending into the said axial recess of the said other hub portion, a threaded bore in the center of the second platelike member for mounting on a spindle of a power driven tool, an inner peripheral recessed edge on the said second platelike member forming a dove-tailed recess in conjunction with an outer peripheral recessed edge on the said other hub portion, connecting means to pull and to hold together the hub and platelike portions after sealingly mounting free end portions of an inflatable cylinder within the said dove-tailed recesses.

7. A buffing and polishing tool comprising a hub composed of a pair of separable telescopically interfitting annular members their combined outer peripheries forming a concave annular surface, an air passageway and control valve in one of the said hub members for regulating the flow of air between its axis and periphery, a partial axial recess in the other of the said hub members, annular recesses in the outer radial surfaces of the said hub members, annular plate members adjacent each said hub member, annular recesses in the inner radial surfaces of the said annular plates opposite the said annular recesses in the said hub members thereby forming dove-tailed recesses, one plate member fitting around the air valve in the said hub member, a projection on the other plate member fitting into the said partial axial recess of the said other hub member, a threaded bore in the said projection for mounting on a spindle, an inflatable flexible cylinder spaced apart and surrounding the said hub having an enlarged inner central portion thereby forming an annular air space of variable cross section in conjunction with the said concave annular outer periphery of the said hub, an annular end wall integral with and extending radially inwardly from each end of the said flexible cylinder and terminating in an annular integral rim surface substantially parallel to the said flexible cylinder, a dove-tailed integral projection extending radially inwardly from the said annular rim surface into one of the said dove-tailed recesses, means interconnecting said plate members and said hub members to sealingly secure the said dove-tailed projections within the said dove-tailed recesses, a replaceable working material mounted on the outer surface of the said flexible cylinder.

BEATRICE W. MONGER,
Administratrix of the Estate of Maynard L.
Monger, Deceased.
